UNITED STATES PATENT OFFICE.

JULIUS HUGO SKOGMAN, OF JOPLIN, MISSOURI.

CABLE-CLAMPING DEVICE.

1,360,458.

Specification of Letters Patent. Patented Nov. 30, 1920.

Application filed April 6, 1920. Serial No. 371,609.

To all whom it may concern:

Be it known that I, JULIUS HUGO SKOGMAN, a citizen of the United States, and a resident of Joplin, in the county of Jasper and State of Missouri, have invented certain new and useful Improvements in Cable-Clamping Devices, of which the following is a specification.

My invention relates to devices for temporarily connecting cables, wires or other flexible members to other members, a purpose of my invention being the provision of a clamping or connecting device of this character which is simple, efficient and durable in construction and which effectively clamps a cable thereto without injury to the cable, the parts of the device being so arranged as to automatically increase the gripping action upon the cable when the tension upon the cable is increased.

I will describe one form of clamping device embodying my invention and will then point out the novel features thereof in claims.

25 In the accompanying drawings:

Figure 1 is a view showing in top plan one form of clamping device embodying my invention.

Fig. 2 is a bottom plan view of the device 30 shown in Fig. 1.

Fig. 3 is a central longitudinal view of the clamp shown in the preceding views.

Fig. 4 is a view showing in front elevation the device shown in the preceding views.

35 Referring specifically to the drawings and particularly to Figs. 3, P and P' designate a pair of plates of like contour which are secured in spaced parallel relation by a rivet 15 at their rear ends, and a pair of pins 16 at their forward ends. The pins 16 are formed with heads at one end and openings at the other end through which a locking pin 17 extends in the manner shown in Fig. 2 to provide a common locking means for 40 retaining the pins within the plates. The rivet 15 supports a securing eye 18 between the plates P and P', as shown in Fig. 3, it being understood that the eye 18 may be permanently connected to a cable or to a

45 stationary object. The pins 16 function as pivots for the rear ends of a pair of links L and L', the links being disposed between the plates P and P' and having their forward ends thickened and bifurcated to provide parallel members 19 and 19^a. The members 19 and 19^a are formed with regis-

tering openings through which rivets 20 extend.

Pivotedly mounted upon the rivets 20 at a point between the members 19 and 19^a are 60 extensions 22 formed on the rear ends of a pair of jaws J and J' which are pivoted at their forward ends on rivets 23 mounted in a bar 24. The jaws J and J' have arcuately and reversely curved gripping edges 25 65 which are serrated as clearly shown in Figs. 3 and 4. As shown in Fig. 2, rectangular shaped washers 26 are mounted upon the rivets 23 at a point between the bar 24 and the heads thereof.

70 As shown in Figs. 2, 3 and 4, the bar is formed on its under side and at a point medially thereof with a bearing 24^a in which is slidably mounted a rod 27. The rear end of the rod 27 is flattened and provided with 75 a head 27^a which is held in firm contact with the plate P' by the locking pin 17 and by recesses formed in the opposite side edges thereof which receive a portion of the pins 16 in the manner shown in Fig. 2. By this 80 arrangement it will be seen that the pins 16 coöperate with the locking pin 17 and thereby prevent longitudinal displacement of the rod, it being understood that the bearing 24^a prevents lateral displacement of the same. 85 Surrounding the rod 27 and interposed between the bearing 24^a and the head 27^a is a coiled expandible spring 28 which serves to bias the bar 24 and consequently the jaws J and J' forwardly into gripping position. 90

The operation of the clamping device is as follows:

The normal position of the jaws J and J' is shown in Figs. 1 and 2 wherein it will be seen that the gripping edges 25 are practically in contact with each other. The releasing position of the jaws J and J' is shown in dash lines in Fig. 1 wherein it will be seen that the links L and L' are spread laterally swinging about the pin 16 as a 100 center.

The jaws themselves move about the rivets 23 as a center and thus cause a separation of the gripping edges 25 to allow of the insertion of a cable therebetween. It will be understood that the jaws J and J' are moved to releasing position by exerting sufficient rearward pressure upon the bar 24 to overcome the tension of the spring 28 and to thus cause the bar to slide rearwardly upon the rod 27. While holding the bar in this retracted position, the cable is inserted be-

tween the jaws J and J', the bar then being released allows the spring to return the same to normal position thereby moving the jaws into gripping position and thereby effectively and securely gripping the cable. When any tension is exerted upon the cable in a direction away from the clamping device, it will be understood that because of the mounting of the jaws and the curvature 10 of the gripping edges, the gripping action will be increased in proportion to the amount of tension exerted upon the cable. It will be further noted that because of the curvature of the gripping edges 25, injury 15 to the cable is prevented while at the same time effectively holding the cable against displacement from the jaws.

Although I have herein shown and described only one form of clamping device 20 embodying my invention, it is to be understood that various changes and modifications may be made herein without departing from the spirit of the invention and the spirit and scope of the appended claims.

25 What I claim is:—

1. A clamping device of the character described comprising, a pair of plates, a pair of links pivoted at one of their ends between the plates, the opposite ends of said links being bifurcated, a bar, jaws pivotally mount-

ed upon said bar, extensions formed on said jaws and pivotally mounted between the bifurcated ends of said links, a bearing formed on said bar, a rod secured to one of said plates and slidably fitted within said bearing, a spring surrounding said rod and engageable with said bar for biasing the latter in a direction to cause said jaws to occupy a gripping position, and a securing eye secured between said plates. 35

2. A clamping device of the character described comprising, a pair of plates, a pair of pins extending through the plates, a locking pin extending through the pins, a pair of links pivoted at one of their ends between the plates, the opposite ends of said links being bifurcated, a bar, jaws pivotally mounted upon the bar, extensions formed on the jaws and pivotally mounted between the bifurcated ends of the links, a bearing 50 formed on the bar, a rod slidably fitted within the bar, a notched head formed on the rod and interposed between and engageable with said pins, a spring surrounding said rod and engageable with said bar for biasing 55 the latter in a direction to cause the jaws to occupy a gripping position, and a securing eye pivotally mounted between said plates. 40 45 50

JULIUS HUGO SKOGMAN.
